SINGLE POLE-DOUBLE THROW SWITCH STRUCTURE

Ted N. Tilman, 3538 Telegraph Drive,
San Jose, Calif. 95132

Filed May 9, 1974, Ser. No. 468,567

Term of patent 14 years

Int. Cl. D13—03

U.S. Cl. D26—13 R

FIG. 1 is a front elevational view of a single pole-double throw switch structure of my design;

FIG. 2 is a rear elevational view thereof;

FIG. 3 is a right side elevational view thereof;

FIG. 4 is a left side elevational view thereof;

FIG. 5 is a top plan view thereof; and

FIG. 6 is a bottom plan view thereof.

I claim:

The ornamental design for a single pole-double throw switch structure, as shown and described.
